CRYPTOGRAPHIC DEVICE

Augusto Vayá, Buenos Aires, Argentina, assignor to C. A. D. A. C. "Compañia Argentina de Aparatos Criptógrafos Sociedad de Responsabilidad Limitada," Buenos Aires, Argentina, a limited-liability company of Argentina

Application November 4, 1954, Serial No. 466,875

6 Claims. (Cl. 35—3)

My present invention refers to a new device for ciphering and deciphering of cryptograms and more particularly relates to an exclusively mechanically operating ciphering and deciphering apparatus so constructed and arranged that without knowledge of the respective code deciphering of a cryptogram prepared by means of this apparatus is rendered practically impossible.

The experiences as hitherto gathered in cryptography have proved that only the modern electronic cryptographic apparatus are able to ensure the impossibility of deciphering the cryptograms. These modern electronic apparatus are, however, very disadvantageous insofar as, at the one hand, they are extremely expensive and, at the other hand, due to their weight and dimensions are entirely unsuitable for being used on any kind of vehicle and finally in case of a sudden danger cannot be instantly destroyed.

The main object of my present invention is to provide a new portable, economic and instantly destructible device for mechanically ciphering and deciphering cryptograms which without knowledge of the code agreed upon by the sender and receiver and without the aid of this device cannot be deciphered at all.

The cryptographic device according to the invention effectively eliminates the disadvantages of the known devices and apparatus and in as far as its portability is concerned, its weight and dimensions may be reduced so far that it may be readily carried along in a pocket or portfolio. It may be manufactured entirely or in its essential parts of an inflammable synthetic material, e. g. Celluloid, so that if necessary it may be quickly burnt.

One important object of my invention is to provide a ciphering and deciphering device comprising at least one rotatively mounted support member, a number of annular cipher carriers loosely arranged on said support member, and a slider with a pair of adjustable needles, projecting over said cipher carriers, the arrangement being such that for the purpose of writing in ciphers a clear text while the point of one needle is used to indicate on different cipher carriers the successive characters composing the clear text, the point of the second needle indicates on the same or other carriers the successive characters of the cryptogram.

Another object of the invention is to provide a ciphering and deciphering device comprising two rotatively mounted support members, a number of annular cipher carriers loosely arranged on each of said support members, and a slider with a pair of adjustable needles so arranged that one needle projects over the cipher carriers of one support member and the other one over the cipher carriers of the second support member, with the advantageous result that while the point of one needle is used to indicate on different cipher carriers of one support member the successive characters of a clear text to be written in ciphers, the point of the other needle indicates on different cipher carriers of the second support member the successive characters of the cryptogram.

According to one advantageous feature of the inven-

2

tion, the arrangement of the cipher carriers on the support members is such that their order of succession may be easily changed so that if each support member comprises a number of e. g. 48 cipher carriers the number of the possible cryptographic combinations will be enormously high, with the result that the higher the number of such possible cryptographic combinations the smaller will be the chance for deciphering the cryptogram.

According to another feature of the invention, the annular cipher carriers have their circumferences preferably subdivided in as many fields as there are characters in the alphabet of a given language with a character of the alphabet reproduced in each field in such an arrangement that the characters of successive fields of the different cipher carriers appear in arbitrary and always different order of succession, so that the order of succession of the characters changes from one to another of the cipher carriers, with the advantageous result that the number of possible cryptographic combinations is considerably increased when changing the relative positions of the cipher carriers, to such an extent that deciphering of a cryptogram is practically rendered impossible.

In connection herewith, according to additional features of the invention, the characters or their backgrounds may be of different colors or may be accompanied by certain marks giving the same another than its conventional signification, whereby the number of possible cryptographic combinations may be further increased.

A further object of the invention is to provide a ciphering and deciphering device as hereinbefore referred to, wherein each supporting member is provided at one end with a fixed toothed disk for its operation and at the opposite end with a nut member for pressing the cipher carriers against said toothed disk for preventing said carriers from freely rotating on said support member, and wherein in the case of two support members the toothed disk of one member is in meshing engagement with that of the second member, with the advantageous result that the operation of one support member causes the other one to rotate in synchronism therewith.

According to another advantageous feature of the invention, the said support members are rotatively mounted in the end walls of a suitable casing in such a manner that they may be readily taken out of said casing, for instance, for the purpose of changing the order of succession of their cipher carriers. Further, in the case of a pair of operatively interconnected support members, at least one of these members at one end is rotatively mounted in a spring-loaded slidable bearing with the advantageous result that for reasons of adjustment the support members may be readily disconnected from one another.

Still another object of the invention is to provide a ciphering and deciphering device as hereinbefore referred to wherein the said slider comprising a pair of adjustable needles is movably mounted on a graduated rail, wherein said needles are extensible and movably arranged on a graduated disk, with the advantageous result that adjustment of said slider along said rail and of said needles to each other may be readily and correctly effected and that the extensibility and adjustability of the needles additionally increases the number of possible cryptographic combinations.

With these objects and advantageous features in view the present invention comprises the arrangement, combination and construction of parts as will be hereinafter fully described with particular reference to the accompanying drawings, whereon a preferred embodiment of the invention has been illustrated by way of example only and whereon:

Figure 1 is a plan view of a ciphering and deciphering

device with a pair of support members for cipher carriers according to the invention;

Figure 2 is a detail partly sectional view of a cylindrical support member illustrating the manner of arranging the cipher carriers thereon;

Figure 3 is a cross sectional view along the line 3—3 of Figure 1.

With reference to the accompanying drawings the ciphering and deciphering device according to the invention comprises a suitable casing 1 having end walls 2. The shafts 3, 3' of a pair of cylindrical support members 4, 4' are rotatively mounted in bearings (not shown) arranged in the end walls 2 of the casing 1. For readily removing the support members 4, 4', the end walls 2 are provided with notches as indicated at 5, 5'.

Each cylindrical support member 4, 4' has loosely disposed thereon a number of annular cipher carriers 6, 6'. The circumference of each cipher carrier is subdivided in as many fields as there are characters in the alphabet of a given language and each field carries a character of this alphabet, but not in the alphabetic order. On the contrary, the order of the succession of the characters is entirely arbitrary and changes from one cipher character to the other. The cipher carriers 6, 6' may be arranged one aside the other, but the same may also be separated from one another by blank ring members 7, 7'. Further individual fields of the cipher carriers 6, 6' or the characters reproduced thereon may be of different colors and certain characters of some or all cipher carriers may be provided with different marks thereby changing the signification of such characters according to their colors or marks as may be agreed upon by the sender and receiver of the cryptograms.

Each of the cylindrical support members 4, 4' has fixedly secured as by screws 18 a toothed disk 8, 8', the two disks 8, 8' forming a gearing for operatively interconnecting the two members so that the operation of one of these toothed disks causes the two cylindrical members 4, 4' to rotate in synchronism with one another.

At its opposite end each cylindrical member 4, 4' is provided with screw threads 9 for receiving a nut member 10, 10'. These nut members act as pressure means for pressing the cipher carriers 6, 6' on the cylindrical members against their fixed toothed disks 8, 8' and for preventing said cipher carriers from spontaneously rotating on said cylindrical members 4, 4'.

The upper edges of the casing walls 2 are provided with studs 11 or the like for removably fastening thereon a rail 12 carrying a slider 13. This slider comprises a pair of adjustable needles 15, 15' capable of being fixed in a desired position by means of a set screw 14. The needles 15, 15' are preferably extensible and so arranged that they selectively project over the cipher carriers 6, 6' of one or both of the support members 4, 4'. If desired, the two needles are movable on a graduated disk 19 secured to the slider 13 for facilitating the relative angular adjustment of the needles 15, 15'. Similarly the rail 12 may also be graduated as shown at 16 and the slider 13 may be provided with a pointer 17 for a correct adjustment of the slider with regard to the cipher carriers 6, 6'.

The bearing (not shown) of the cylinder shaft 3 at its end carrying the toothed disk 8 is conveniently arranged in a slidable manner and subject to the pressure of a suitable spring (not shown) so that the gearing 8, 8' may be disengaged for the relative adjustment of two support members 4, 4'.

Instead of two support members 4, 4' the device may comprise only one support member 4, in which case the two needles are adjusted so as to project over two different cipher carriers 6 of this one support member only.

The operation of the ciphering and deciphering device according to the present invention is simply as follows:

It is absolutely indispensable that sender and receiver have their ciphering and deciphering devices with exactly identical cipher carriers i. e. the orders of succession of

the characters on the different cipher carriers of the two devices must be exactly the same. Further, the orders of succession of these cipher carriers in the two devices must be also identical. The arrangement of the cipher carriers may be readily effected after removing the nut members 10, 10'. The relative position of the cipher carriers is adjusted in accordance with a code agreed upon by the sender and receiver in such a manner that the characters of the successive cipher carriers compose a clear text sentence which forms part of the code. In addition to this sentence the code must include a number e. g. "160" characterizing the angle formed by the two needles 15, 15' and a second number e. g. "10" indicating the 10th cipher carrier at which the ciphering operation is started.

After effecting the adjustments in accordance with the code as hereinbefore referred to a cryptogram is prepared in the following manner:

In the position as shown in Fig. 1 with the needle 15' projecting over the 10th cipher carrier 6' the cylinder 4' is rotated until on said cipher carrier below the point of the needle 15' appears the first character of a clear text to be written in ciphers, at which moment the point of the needle 15 indicates the first character of the cryptogram. Now the slider 13 is moved to the next position to the right or to the left as agreed upon, the cylinder 4' is again rotated until the second character of the clear text appears below the point of the needle 15' and the second character of the cryptogram is indicated by the point of the needle 15. These operations are repeated until completion of the cryptogram. For deciphering the same the receiver proceeds in the same, but inverted manner by rotating the cylinder 4 and reading the clear text on the cylinder 4'.

It will be understood that the present invention is by no means restricted to the embodiment as described and shown, but that amendments and alterations may be made therein and that such amendments and alterations have to be considered as falling within the scope of the invention as clearly set forth in the appended claims.

What I claim as new and desire to secure by Letters Patent is:

1. Cryptographic device for ciphering and deciphering cryptograms, comprising a casing, at least one cylindrical support member rotatively and removably mounted in the end walls of said casing, a number of interchangeable and individually adjustable annular cipher carriers on said support member and provided on their circumferences with the arbitrarily arranged characters of the alphabet in orders of succession differing from one cipher carrier to another pressure means in connection with said support member for fixing on the latter said cipher carriers in their adjusted positions, a rail removably mounted on the upper edges of said end walls in a position parallel to the axis of said support member, and a slider with a pair of relatively adjustable needles carried by said rail and arranged with said needles projecting over said cipher carriers.

2. Cryptographic device for ciphering and deciphering cryptograms, comprising a casing, at least one cylindrical support member rotatively and removably mounted in the end walls of said casing, a number of interchangeable and individually adjustable annular cipher carriers on said support member between a fixed driving member at one end and a removable pressure member at the opposite end of said support member and provided on their circumferences with the arbitrarily arranged characters of the alphabet in orders of succession differing from one cipher carrier to another, a rail removably mounted on the upper edges of said end walls in a position parallel to the axis of said support member and a slider with a pair of relatively adjustable needles carried by said rail and arranged with said needles projecting over said cipher carriers,

3. Cryptographic device for ciphering and deciphering cryptograms, comprising a casing, a pair of parallel cylindrical support members rotatively and removably mounted in the end walls of said casing, a number of interchangeable and individually adjustable annular cipher members between a fixed toothed disk at one end and a removable pressure member at the opposite end of each support member, the toothed disks of both support members being in operative engagement with each other and the circumferences of said cipher carriers being provided with arbitrarily arranged characters of the alphabet in orders of succession differing from one cipher carrier to another, a rail removably mounted on the upper edges of said end walls in a position parallel to the axes of said support members and a slider with a pair of relatively adjustable needles carried by said rail and arranged with said needles projecting over said cipher carriers.

4. Cryptographic device for ciphering and deciphering cryptograms, comprising a casing, at least one cylindrical support member rotatively and removably mounted in the end walls of said casing, a number of interchangeable and individually adjustable annular cipher carriers loosely arranged on said support member and provided on their circumferences with the arbitrarily arranged characters of the alphabet in orders of succession differing from one cipher carrier to another, a graduated rail removably mounted on the upper edges of said end walls in a position parallel to the axis of said support member and a slider movably mounted on said rail and provided with a pair of relatively adjustable needles arranged on a graduated disk carried by said slider and projecting over said cipher carriers.

5. Cryptographic device for ciphering and deciphering

cryptograms, comprising a casing, at least one support member rotatively mounted within said casing, a number of interchangeable and individually adjustable cipher carriers on said support member, pressure means in connection with said support member for fixing thereon said cipher carriers in their adjusted positions, and a slider with a pair of relatively adjustable needles arranged on a rod member secured to opposite walls of said casing in a position parallel to the axis of said support member and with said needles projecting over said cipher carriers.

6. Cryptographic device for ciphering and deciphering cryptograms, comprising a casing, a pair of rotatively mounted and operatively interconnected parallel support members within said casing, a number of interchangeable and individually adjustable cipher carriers on each of said support members, pressure members in connection with said support member for fixing thereon said cipher carriers in their adjusted positions, a slider with a pair of relatively adjustable needles, arranged on a rod member secured to opposite walls of said casing in a position parallel to the axes of said parallel support members and with said needles capable of projecting over the cipher carriers on said two support members.
